SECTIONAL COPPER PAN FOR WINDOW
AND WALL CONSTRUCTIONS

Joseph Ludden, New York, N. Y.

Application August 15, 1936, Serial No. 96,147

10 Claims. (Cl. 189—75)

This invention relates to new and useful improvements in a copper or other material pan for the tops of window openings.

The invention has for an object the construction of a device as mentioned which is characterized by the fact that it is composed of a plurality of sections adapted to coact with each other to produce a single efficient unit.

Still further the invention contemplates the provision of a base section consisting of a rectangular base portion having flanges upon one side and two ends, and a lip on the other side formed by a long center section and several short detachable end sections and adapted to extend 15 and fit across the top of the window openings to shed rain water, melted snow, and other liquids.

Still further the invention proposes the provision of several odd and even sections adapted to coact with each other and with the base section 20 and to comprise intermediate sections between the base section and a main top section.

It is proposed to arrange the odd sections with a wall portion adapted to engage against the inner face of said flange of the base section of an adjacent even section and to have end flanges to engage the inner faces of the end flanges of an associated even section.

It is proposed to construct the even sections to include a wall portion to extend across and above 30 the end flanges of the adjacent odd sections, and furthermore to include end flanges adapted to be associated with complementary end flanges upon the odd sections.

With respect to the top section it is contemplated to arrange this section with a large base portion surrounded by flanges and formed with a cutout from which edge portions are bent downwardly and arranged to engage portions of an adjacent odd or even section, as the construction 40 may be.

For further comprehension of the invention, and of the objects and advantages thereof, reference will be had to the following description and accompanying drawings, and to the appended 45 claims in which the various novel features of the invention are more particularly set forth.

In the accompanying drawings forming a material part of this disclosure:—

Fig. 1 is a fragmentary front elevational view 50 of a portion of a building showing the outer side thereof in the vicinity of the upper edge of a window opening.

Fig. 2 is a perspective view of the copper or other material pan illustrated per se.

Fig. 3 is a perspective view of the base section 55 per se.

Fig. 4 is a perspective view of one of the odd sections per se.

Fig. 5 is a perspective view of one of the even 60 sections per se.

Fig. 6 is a perspective view of the top section per se.

Fig. 7 is a sectional view taken on the line 7—7 of Fig. 2.

Fig. 8 is a similar view to Fig. 7 showing the copper pan in use in a building wall.

The copper or other material pan, according to this invention, comprises a base section 10, several odd sections 11, several even sections 12, and a top section 13. In Fig. 2 these various sections 10 are shown assembled. In Fig. 1 they are shown plastered into the wall.

The base section 10 consists of a rectangular base portion 10^a having a flange 10^b on one of the sides thereof and connecting with end flanges 10^c. At the front the base portion 10^a is provided with a long center extending lip 10^d, and a plurality of short detachable end lips 10^e separated from lip 10^d and from each other by slots 10^f, and are adapted to slightly project from the wall directly 15 over the window opening and act as a drip edge. The end sections 10^e project from the base portion 10^a and are provided with perforations, scoring, etc., at their joining lines so that any number 20 of sections 10^e may be removed by breaking them off at the lines of perforations, scoring, etc., for the purpose of fitting the particular change in bond in the brick layout at the window opening.

Each odd section 11 consists of a rear wall portion 11^a and end flange constructions 11^b. These 30 end flange constructions are adapted to zig-zag between the bricks of the wall. Each flange construction consists of an end flange portion 11^b extending from the bottom upwards substantially midway of the height of the wall portion 11^a and 35 continuing into inward extending horizontal continuations 11^c, in turn continuing into vertical end flanges 11^d.

Each of the even sections 12 consists of a wall portion 12^a and end flange constructions 12^b. 40 Each of these end flange constructions is of zig-zag formation to extend between the bricks of the wall. Specifically, it comprises a top end flange 12^b extending substantially one half the width of the wall 12^a and continuing into an inward directed portion 12^c which in turn continues into a downward directed vertical portion 12^d.

The top section 13 consists of a large rectangular base portion 13^a having flanges 13^b and 13^c on its inner side and at its two ends respectively. 50 At the front portion the base portion 13^a is formed with a cutout 13^d having flanges 13^e and 13^f on the inner side and two ends respectively.

The various sections of the pan are assembled 55 as clearly shown in Figs. 1, 2 and 7. Starting from the base section 10 one of the odd sections 11 is set into the base section so that the wall 11^a is disposed adjacent the near face of the wall 10^b and the flanges 11^b adjacent the inner faces of the flanges 10^c. An even section 12 is then en- 60

gaged on the odd section 11 by engaging the wall portion 12^a against the near face of the wall portion 11^a and engaging the flanges 12^b upon the inner faces of the flanges 11^d. In this manner 5 any number of odd and even sections may be built upwards. At the top the structure is shown terminating in an odd section. The top section 13 is adapted to engage this odd section by reason of having the flange 13^e engaging against the 10 near side of the flange 11^a and having the end flanges 13^f engaging the inner faces of the flanges 11^b.

The bricks are built into the pan and around the pan so that the wall is solid and the materials 15 of the pan extend merely between the bricks of the wall. It should be noted that the edges of the sections of the pan are arranged to drain water into the base section 10 from which the water will be drained out over the lips 10^d and 10^e. 20

20. A plurality of wall ties 14 project from the back face of the pan sections 13, 11 and 12, in staggered relation for bonding the bricks of the wall in one way, against displacement.

While I have illustrated and described the preferred embodiments of my invention, it is to be understood that I do not limit myself to the precise constructions herein disclosed and the right is reserved to all changes and modifications coming within the scope of the invention as defined 30 in the appended claims.

Having thus described my invention, what I claim as new, and desire to secure by United States Letters Patent is:—

35. 1. A copper or other material pan for the tops of window openings comprising a base section, several odd and even sections, and a top section.

2. A copper or other material pan for the tops of window openings comprising a base section, 40 several odd and even sections, and a top section, said top section consisting of a large rectangular base portion with a surrounding flange and a cutout at its front edge, said cutout being provided with flanges adapted to engage the flanges of an adjacent section.

45. 3. A copper or other material pan for the tops of window openings comprising a base section, several odd and even sections, and a top section, said base section comprising a base portion having flanges on one side and two ends and a draining lip on the other side.

4. A copper or other material pan for the tops of window openings comprising a base section, several odd and even sections, and a top section, 55 said base section comprising a base portion having flanges on one side and two ends and a draining lip on the other side, said draining lips being constructed of a long center portion and a plurality of short spaced end portions.

60. 5. A copper or other material pan for the tops of window openings comprising a base section, several odd and even sections, and a top section, said base section comprising a base portion having flanges on one side and two ends and a draining lip on the other side, said draining lips being constructed of a long center portion and a plurality of short spaced end portions, said end portions being joined to the base section by scoring, 65 perforations, or the like.

70. 6. A copper or other material pan for the tops of window openings comprising a base section, several odd and even sections, and a top section, certain odd and even sections consisting of wall portions and end flange constructions adapted 75 to inter-engage.

7. A copper or other material pan for the tops of windows comprising a base section consisting of a rectangular base portion having flanges on one side and two ends and a lip on the other side, an odd section adapted to set into 5 said base section and consisting of a wall portion to engage against the inner face of said side flange and materially extending above it and having end flanges to engage the inner faces of said end flanges, said end flanges being associated with inwardly extending horizontal continuations connecting with additional end flanges, an even section adapted to set into said odd section and consisting of a wall portion to engage the inner face of said wall portion and extending 10 above it and also having end flanges to engage the inner faces of said latter-mentioned end flanges and associated with horizontal outwardly extending continuations connecting with additional end flanges, additional odd and even sections inter-engaging each other, and a top section 15 consisting of a large rectangular base portion having flanges on one side and two ends and at the other side having a cutout formed with flanges adapted to engage the flanges of the 20 uppermost of said sections.

8. A copper or other material pan for the tops of windows comprising a base section consisting of a rectangular base portion having flanges on one side and two ends and a lip on the other side, an odd section adapted to set into said base section and consisting of a wall portion to engage against the inner face of said side flange and materially extending above it and having end flanges to engage the inner faces of said end flanges, 30 said end flanges being associated with inwardly extending horizontal continuations connecting with additional end flanges, an even section adapted to set into said odd section and consisting of a wall portion to engage the inner face of said wall portion and extending above it and also having end flanges to engage the inner faces of said latter-mentioned end flanges and associated with horizontal outwardly extending continuations connecting with additional end flanges, 35 additional odd and even sections inter-engaging each other, and a top section consisting of a large rectangular base portion having flanges on one side and two ends and at the other side having a cutout formed with flanges adapted to engage the flanges of the uppermost of said sections, the flanges from an upper section always engaging the inner faces of the flanges of an inner lower section.

9. A copper or other material pan for the tops 55 of window openings comprising a base section, several odd and even sections, and a top section, certain odd and even sections consisting of wall portions and end flange constructions adapted to inter-engage, a plurality of wall ties projecting from said odd and even sections for bonding the bricks of the wall in one unit against displacement.

10. A copper or other material pan for the tops 65 of window openings comprising a base section, several odd and even sections, and a top section, certain odd and even sections consisting of wall portions and end flange constructions adapted to inter-engage, a plurality of wall ties projecting from said odd and even sections for bonding the 70 bricks of the wall in one unit against displacement, said wall ties in the even sections are in staggered relation with the wall ties in the odd sections.
